TRAVELLER-APPLYING TOOL

Filed Oct. 14, 1944

UNITED STATES PATENT OFFICE

2,418,209

TRAVELLER-APPLYING TOOL

Roger B. Watts, Nashua, N. H., assignor to Whitin Machine Works, Whitinsville, Mass., a corporation of Massachusetts

Application October 14, 1944, Serial No. 558,766

2 Claims. (Cl. 29—207)

1

This invention relates to a tool for applying a traveller to a spinning or twisting ring, and relates more particularly to a tool for applying a relatively heavy traveller to a large ring of the vertical flange type. Such travellers are made of stiff and heavy wire and necessitate the application of substantial force to snap the traveller over the vertical flange of the ring and into running position.

It is the general object of my invention to provide an improved hand tool for effecting the above defined operation.

A further object is to provide a tool having provision for storage of a supply of travellers and for semi-automatic feed of successive travellers to applying position, together with means to release the selected traveller and to force it over the vertical flange to operative or running position.

My invention further relates to arrangements and combinations of parts which will be herein-after described and more particularly pointed out in the appended claims.

A preferred form of the invention is shown in the drawings, in which

Fig. 1 is a side elevation of my improved tool, with a ring shown in section;

Fig. 2 is a sectional plan view thereof, taken along the line 2—2 in Fig. 1;

Fig. 3 is a side elevation of a cam plate and lever to be described;

Fig. 4 is a plan view of a storage member;

Figs. 5, 6 and 7 are detail end elevations, looking in the direction of the arrow 5 in Fig. 1 and showing successive positions of certain operative parts; and

Figs. 8, 9 and 10 are detail views showing successive steps in the application of a released traveller to a vertical flange ring.

In the drawings, I have shown a portion of a vertical-flange type twister ring R mounted in a ring rail 15. My improved traveller-applying tool comprises a main bar or support 20 adapted to rest on the top of the ring R and having an offset end portion 21 engaging the inner face of the ring.

The travellers T may have the usual outline shown in Fig. 8 and are assembled on an upwardly extending storage bar 25 which is secured to the top of the bar 20 in any convenient manner as by a screw 26.

A guard 30 in the form of an inverted U-shaped member is mounted on the bar 20, to the left of the storage bar 25 as viewed in Fig. 1. The guard supports a cross-pin or stud 32 on

2

which a feed lever 33 is pivoted. A spring 34 is centered on the stud 32 and acts to force the right-hand or operative end 35 of the lever 33 to the depressed or holding position shown in Figs. 5 or 7.

5 A cam plate 40 (Fig. 3) is mounted on a lever 41, which lever is pivoted at 42 to a bracket 43 secured to the end portion 21 of the bar 20 and having a flange 44 projecting under the ring R. The cam plate 40 has a traveller-engaging end portion 45 and a cam-shaped pressure-applying portion 46.

10 A spring clip 50 may be provided to prevent displacement of the travellers in storage on the storage bar 25, and the upper end portions 52 and 53 of the storage bar may be oppositely beveled to facilitate application of travellers thereto.

15 Having described the details of construction of my improved traveller-applying tool, the method of its operation and use is as follows:

20 The offset end portion 21 of the tool is inserted through the ring R and the flange 44 is hooked under the ring. The lever 41 is then pressed downward sufficiently to elevate the traveller-retaining end 35 of the feed lever 33. The end 35 is thus moved to the position shown in Fig. 6 and the lowermost traveller T is released for movement to the advanced position also shown in Fig. 6, such movement being effected by the 25 weight of the travellers assembled on the storage bar 25.

25 The lever 41 is then swung upward, raising its cam plate 40 to the position shown in Fig. 7. At the same time, the feed lever 33 is released and the spring 34 pushes the end 35 of the lever downward to the position shown in Fig. 7, permitting the lowermost traveller only to move under the cam plate 40 (Fig. 7) and to then drop to the position shown in Fig. 8. At the same 30 time, the end 35 of the lever 33 holds back the remaining travellers, as indicated in Figs. 5 and 7.

35 The lever 41 is then moved downward to engage its cam plate 40 with the released traveller T, as shown in Fig. 8, and substantial pressure is then applied to the lever 41, as indicated in Fig. 9. Such application of pressure causes the cam portion 46 of the cam plate 40 to depress and distort the traveller sufficiently to snap the lower 40 end of the traveller under the lower flange of the ring R to the running position shown in Fig. 10. During this application of downward pressure, the part 45 of the cam plate prevents transverse displacement of the traveller.

45 The traveller T is shown in Fig. 9 at the point

where it is just about to snap under the lower edge of the vertical flange.

The traveller T is thus quickly and easily applied and placed in running position, after which the applying tool is removed and is available to apply another traveller to any other ring requiring traveller replacement.

The entire traveller-applying operation is carried out by first slightly depressing the lever 41, then substantially raising the lever, and finally again depressing the lever and applying firm pressure thereto, all of which operations may be quickly and easily performed manually by the operator.

Having thus described my invention and the advantages thereof, I do not wish to be limited to the details herein disclosed, otherwise than as set forth in the claims, but what I claim is:

1. A tool for applying travellers to vertical-flange type rings comprising a traveller storage, a feed lever, a spring to move said feed lever to traveller-retarding position, a hand lever effective to rock said feed lever and advance a single traveller, and a cam plate on said hand lever movable in one direction to release said advanced traveller and movable in a reverse direction to engage said released traveller and to transmit manual pressure from said hand lever to said traveller to snap said traveller over the lower edge of said vertical flange.

2. A tool for applying travellers to vertical-

4

flange type rings comprising a traveller storage, a feed lever, a spring to move said feed lever to traveller-retarding position, a hand lever effective to rock said feed lever and advance a single traveller, and a cam plate on said hand lever movable in one direction to release said advanced traveller and movable in a reverse direction to engage said released traveller and to transmit manual pressure from said hand lever to said traveller to snap said traveller over the lower edge of said vertical flange, said cam plate when in lowered position preventing escape of the lowermost traveller from storage and said feed lever preventing advance of the next to the lowermost traveller when said lowermost traveller is released.

ROGER B. WATTS.
